UNITED STATES PATENT OFFICE.

DAVID KUNHARDT, OF AACHEN, PRUSSIA, GERMANY.

ELECTRIC TELEGRAPH.

SPECIFICATION forming part of Letters Patent No. 379,016, dated March 6, 1888.

Application filed January 22, 1887. Serial No. 225,077. (No model.)

To all whom it may concern:

Be it known that I, DAVID KUNHARDT, of Aachen, Prussia, Germany, have invented new and useful Improvements in Electric Telegraphs, of which the following is a specification.

This invention relates to improvements in electrical telegraphs and appliances to be used in connection therewith; and the object of my invention is to provide means for transmitting telegrams with extraordinary speed in a manner that the improved telegraph of my invention may well be termed a "quick telegraph." This object is obtained by means of a single shaft, to which rotary motion is imparted by any suitable driving-power, and to which shaft any suitable number of separate telegraph apparatuses provided with the improvements hereinafter described are connected. Every one of these apparatuses may be used independently by an operator; but as great as the number of such apparatuses connected to one common shaft may be, one single line will be sufficient to connect the transmitting and receiving station.

In order to make the nature of my invention and in what manner it is to be performed better understood, I refer to the accompanying drawings, in which—

Figure 1 shows an operator in action at the side of the apparatus. Fig. 2 is a front view of the cone; Fig. 3, a plan view of the same, and Fig. 4 represents an arrangement for co-temporary correspondence with several stations. Figs. 5 to 14 represent details of the apparatus at an enlarged scale. Fig. 15 is a partial longitudinal section through the receiving apparatus. Fig. 17 is a front view, Fig. 18 an end view, and Fig. 16 a plan, of this apparatus shown in Fig. 15. Fig. 19 shows a longitudinal section, Fig. 21 a cross-section, and Fig. 20 a plan, of a similar apparatus. Figs. 22 to 24 are details of another but more complicated receiving apparatus. Fig. 25 is a front view, and Fig. 26 a side view, partly in section, of the writing apparatus of the receiving-station. Fig. 27 is a front view, and Fig. 28 a side view, partly in section, of a self-acting interrupter. Fig. 29 is a front view, Fig. 30 a side view, partially in section, Fig. 31 a plan, and Fig. 32 a horizontal section, of a writing apparatus arranged in a different manner. Fig. 33 is a side view, Fig. 35 a

cross-section, and Fig. 36 a horizontal plan, partly in section, of one of the relay apparatus of the receiving-station, and Fig. 34 the corresponding cross-section of the other relay apparatus. Figs. 37, 37^a, 38, 38^a, 39, and 39^a represent the circuit of the current of the whole apparatus. In these figures the contacts of the relay apparatus are attached directly to the anchor, while in Figs. 33 to 36 the contacts are shown on the counter-weight of the anchor. Figs. 40 to 48 illustrate a modification of the receiving apparatus.

The combination of the whole apparatus is as follows: Upon a vertical shaft, A, bearing in the frame B, Figs. 1 to 4, a cone, C, is fixed, to which rotation is imparted from the shaft A. The rotation of the shaft A may be effected by a motor in combination with a suitable transmission.

Several cones C are placed the one beside the other, and every cone may be set to work by an operator. The cone C bears on its circumference a number (say three) of alphabets of Morse-type system. Into the mouths of the cone plates d are inserted, fitted with short and long bosses e, according to the points and strokes of the Morse-type system, Fig. 14.

Into the upper face of the cone C contact-plates a, b, and c (see Figs. 36, 37, 39^a) are inserted, the position of these corresponding to the position of the type-plates d, and of the same number, say, for each alphabet, three contact-plates, a b c. These contact-plates a, b, and c may also be arranged upon special disks C' (see Fig. 4) on the shaft A. The number of the disks C' corresponds to the number of the stations to which one and the same telegram should be sent at the same time, and also the type-plates d may have the same number of bosses e, placed the one beside the other, or they may have a corresponding breadth.

To the frame B, over each of the cones C or disks C', a bridge, B', is fastened. (See Figs. 1, 3, 4, 5, 6, 7, 8.) The bridge bears the contact-springs 1, 2, 3, 4, 5, 6, 7, and 8, sliding upon the upper face of the cone C or of the disk C'. The springs are insulated. Only the springs 2 and 4 are connected to spring 5. Spring 6 is double. Springs 7 and 8 are fitted with binding-screws.

The bridge B' bears a U-shaped frame, f, containing the commutator, (Figs. 1, 5, 6, 7,

8, 9, and 10,) consisting of a wooden plate, g , adapted to a lever, g' , and fitted with the contact-points g^2 g^3 g^4 g^5 g^6 g^7 g^8 .

Figs. 37 to 39^a show plate g in perspective and without the lever g' to give a better understanding. Plate g is turning round two bolts adapted to the arm g' and bearing in the frame f , and is pressed constantly against the contact-springs h^2 h^3 h^4 corresponding to the contact-points g^2 by spring g^9 .

To the upper face of the cone C or disk C' a strong spring, i , is adapted, which counteracts the action of spring g^9 , when in turning the cone it passes just below the outer part of the arm g' and presses down plate g , and it opens the contacts g^2 h^2 , g^3 h^3 , and g^4 and h^4 , and closes the contacts g^5 h^5 , g^6 h^6 , g^7 h^7 , and g^8 h^8 . (See Figs. 8 and 39.) The contact-points g^2 , g^4 , g^6 , and g^8 on the plate g are connected by metallic straps, and in the same manner g^5 and g^8 are connected. g^3 is totally insulated from the others and connected to the + pole of a battery, D'. The contact-springs h^2 and h^5 are connected to the earth-plate E of the delivering-station; h^4 and h^6 to the - pole; h^8 to the + pole of the battery D' of the delivering-station. Spring h^3 is connected by a wire to the sliding spring 3, and spring h^7 to the sliding spring 1.

Before the cone C, Fig. 1, a frame, B², is adapted, into which the keys K are disposed movably. They are held always in elevated position by a spring, K². (See Figs. 11, 12, 13.) The keys are alternated to the right and to the left for sparing space, and a disk, K', on the one end shows the corresponding type or sign. In consequence of that the keys must be arranged in the same number as the signs. Every key has on the opposite end toward the cone an insulated spring, l , fitted with a nose, m . Between the latter and the key-lever a second insulated spring, l' , is adapted, a small distance from the former. These noses m are just opposite to the noses e , fixed upon the cone C, and are pushed back, if the key be pushed downward, to bring in contact spring l with the spring l' . The key may not be held down by the operator so long as the type-plate passes, and for that purpose the following arrangement is adapted:

Every key bears sidewise a toothed aglet, K³, into whose teeth a hook, K⁶, is gearing, movably fitted to the frame B² by an angle-lever, K⁴, and pressed against K³ by a spring, K⁵. If one key is pushed down, hook K⁶ will hold it so until a nose, e' , fixed upon the type-plate d sidewise of the end of the last nose, e , pushes against the lower end of hook K⁶ and disengages it to make the key Karise. The binding-screw n of every key is in contact with spring l and screw n' with the spring l' . Besides, from every binding-screw n a wire goes to the sliding spring 8, and from every binding-screw n' a wire to the sliding spring 7, and always one wire to the line-band and to the line.

If a key is pushed down when the cone C is

turning, the key will remain down so long as the type-plate d passes with its short and long elevations e below the nose m . By this action there will be effected between the springs l and l' a long or a short contact, corresponding to the form of the passing nose e . The open or closed current will effect in the receiving-station, by the arrangement described in the following, signs corresponding exactly to the passing type. The type being passed, the key will rise immediately, as mentioned before.

The receiving apparatus of the receiving-station is represented in Figs. 17 to 30 of the accompanying drawings. The receiving-station is fitted with the same number of receiving apparatuses as there are cones C in the delivering-station. These accepting apparatuses are connected together and with the secondary apparatus and batteries, as shown in Figs. 37, 37^a, 38, 38^a, 39, 39^a. Figs. 15, 16, 17, and 18 show such a receiving apparatus; Figs. 19 to 24^a, modifications of the same. The former is fitted with the magnets F, G, and H upon a wood frame. Shoe-magnet F is provided with an anchor, F', movably fixed to one end of the double lever F², turning around screw-pivots. The other end of the lever is leaning upon anchor G' of the magnet G, fixed to the similarly-shaped and similarly-supported lever G². Anchor G' is leaning by means of an insulated plate, o, upon an also insulated plate, o', of the anchor H' of magnet H. Anchor H' is fixed to the double lever H².

All the three anchors are drawn off from their appertaining magnets by springs. If the anchor F be attracted, also the two anchors G' and H' will be pushed upon their magnets. If G' be attracted, F' will be remaining, and only H' will be pushed downward.

The attraction of H' will be effected by the magnet H without influencing the two others. The anchor F' bears on its upper end a metal point, p, which is leaning against the plate p' if the anchor be attracted, and on its lower end the contact-point q, leaning upon q' when in tranquillity. Anchor G' is fitted at its upper end on the one side with the contact-point r and on the other side with the point s, the former leaning in tranquillity against r', the latter against s'. On the bottom of one side point t, on the other side the two points u and v, are fixed, (in Fig. 17 v is placed behind u,) all the three leaning against the springs t' u' v'. (v' is placed behind u'.) The springs u' and v' are provided with stops w and w' to limit their motion. w has also contact, but not w', the anchor of plate o'. Besides, H' is fitted with noses X Z, pushing upon the springs X' and Z', and being in contact with them when the anchor will be attracted.

In the modification shown in Figs. 19 to 24 of this receiving apparatus all the anchors are moved up and down vertically, and are suspended by springs and fitted with guiding-tags. The contacts and also the effects are the same as of the arrangement described.

The relays represented in Figs. 33 to 36 is formed by two electro-magnets, K, and by two constant rod-magnets, K', the latter being fixed to opposite ends of the lever K², movable between points. The anchors K' will be drawn off by the counter-weights K³ from the magnet-poles. The one anchor K' (between the electro-magnet spools) bears the contact-pencils a² and e². If K' is attracted, e² is leaning 5 against e³. (See Fig. 34.) The other anchor K' is fitted with three contact-pencils, i² o² u², also placed between electro-magnet spools. If in tranquillity, i² is pressed against i³ by the counter-weight. If the magnet-anchor be attracted, o² is pushed against o³ and u² against u³.

The current passes through the relay apparatus and is working, as described, in the following manner: The current effects an attraction of the magnet K' in the first magnet K', because the position is of that sort as the different poles are opposite in normal current around K. Consequently contact is effected between e² and e³; and contact is broken between a² and a³. In the second magnet K the same poles are called forth; but the second magnet-anchor, K', is opposite as the same poles are opposite. There will remain contact between i² and i³, and contact will remain broken between o² and o³ u² and u³. If a reversed current passes through the magnets K, the poles are changed and attraction is effected (see Fig. 39^a) of the second magnet K' with contact o² o³ and u² u³, contact i² and i³ is broken, first magnet K' is pushed off and contact a² a³ is closed, and contact e² e³ is opened.

From all these contacts a² a³ e² e³ o² o³ u² u³ i² i³ the local current is opened and closed from battery N. (See Figs. 37^a, 38^a, 39^a.) Normal current from the line is answered by contacts of transmission of a normal current of the local battery N into the receiving apparatus to the changed current from the line answers the contacts of the changed local-battery current.

The writing apparatus consists of a single or double electro-magnet L, (see Figs. 25 to 45 33,) the pole of which is opposite to an electro-magnet, L', kept off from it by a spring. In lieu of the electro-magnet L' may also be adapted a constant rod-magnet, as shown in Figs. 27 and 28. The same arrangement is supposed in Figs. 37 to 39^a. This anchor is working to a writing-point by lever-gearing in such a manner as to produce attraction of L by L' and type-writing upon a paper strip rolling down as soon as normal current of the local battery N exists.

Figs. 27 and 28 show an interrupter formed by the electro-magnet M and the constant rod-magnet M', pushed off by a spring. The rod-magnet M' is fitted at its upper end with a contact-point, v², leaning against plate v³ if normal current exists, but pushed off if the current is changed. Besides the relay-battery N there appertain two batteries, O and P, to every receiving apparatus. The combination of these batteries with the receiving apparatus, the writing apparatus, and the relay apparatus, and also the combination of the apparatus

one to the other are represented in Figs. 37 to 39^a. In the delivering-station three cones are supposed, and correspondingly three receiving apparatuses in the receiving-station.

The operation of the whole apparatus is as follows, (see Figs. 37 and 37^a.) The receiving-station is invoked from the delivering-station, and in the receiving apparatus E III the anchor H' is pushed down. By this contact Z Z' is closed. Z' is connected to the positive (+) pole of battery O'. The current takes its way from there to the + pole Z' Z, magnet H in E III, o o' in E I — pole of o' in E III. This current keeps now fast the anchor H' upon magnet H. If the cone C of the delivering-station is turning, the springs 3 and 4 will slide upon the plate a, and the springs 5, 6, and 7 upon the plate a'. The contact-plate g of the commutator is elevated—to wit, g² leans against h², g³ against h³, and g⁴ against h⁴. The closing-current passes as follows: Beginning in the delivering-station at the positive pole of the battery D', it passes to the contact g³ h³, spring 3, 80 plate a, spring 4 5, plate a', spring 7, binding-screw n', line-strip and line-relay apparatus of the receiving-station, earth-plate E' of the same, returns to the earth-plate of delivering-station, contact h² g² h⁴ g⁴ — pole of the battery 95 D'. This first current is a normal current, and therefore calls out the effect mentioned before. Contact a² a³ is opened, e² e³ is closed, contact i² i³ remains closed, and o² o³ and u² u³ remain open.

The current of the relay-battery N takes the following way: + pole of N point I, contact e² e³ point II. From there a wire passes in each receiving apparatus to contact-point x. Preliminary in E III is only closed at x x' the current passes from x x' to r r' in E III, and from there to the magnet M in E I. Here it causes no effect, because magnet M' is a constant rod-magnet, and is so arranged that the poles of it are opposite to the equivalent poles of M when normal current exists, that also attraction will not exist. From M the current passes contact w w', (see Fig. 17,) magnet F in E I, to contact s s' in E III, to point III, contact i³ i², and point III to negative pole of the battery N. The current 105 passes also around magnet F' in E I. By this the anchor F' is attracted, and at the same time the anchors G' and H' go down upon the magnets G and H. (The intervals of the anchors G' from G and H' from H must be just equidistant to allow the anchors to affix to the appertaining anchors at the same time. The interval between F and F' may be larger, because F' must not be affixed upon F.) By 110 the going down of G' in E I contacts r r', s s', and u' w were opened, and t t' v v' closed. The contacts u, w, and v v' are shown one beside the other in Fig. 37 to 39^a, to preserve clearness.

In reality they are arranged one after the other. By going down of F' contact p p' is opened and contact q q' closed. By going down of H' contact x x' and z z' are closed. By the latter the current of battery O' is closed and

takes its way as follows: Positive pole of O' , contacts $z z'$, magnet H , contact $o o'$ in $E\ II$, negative pole of O' . The magnet H takes also fast anchor H' . By contact $t t'$ the current of 5 the battery P' was closed and took its way: positive pole of P' , contact $t t'$, $v^2 v^3$, magnet G , negative pole of P' . The anchor G' is also affixed upon G . During the going down of F' and G' the following altering of the current in 10 E took place: The current passed in the beginning $w\ u'$ to F , but immediately u' was pushed off from w by pencil u . To avoid a current interruption, q pushed upon q' and the current passed from w over $q\ q'\ u'$ to F , 15 &c., it was also not altered. This altering of the current is necessary, because the current interruption may not depend from the contact interruption between w and u' , but from the sliding of the springs 3, 4, 5, and 7 upon the 20 plates a and a' in the delivering apparatus.

In the following is given a description of the single contacts: By going down of the three anchors F' , G' , H' the contacts $v\ v'$ and $s\ s'$ must be delivered, first, next to this contact $q\ q'$ must happen, thereafter contacts $t\ t'$ and $u\ u'$ —to wit, contact is opened between w and u' by pushing off u to u' . u itself has no influence to the conduct. Thereafter follow the contacts $x\ x'$ and $z\ z'$ and the anchors push 25 upon the magnets. By finishing of the sliding of the springs 3, 4, 5, and 7 upon the plates a and a' the current 1 of the battery D' is interrupted; by that the contact $e^2 e'$, and also the current 1 of the battery N in the 30 receiving apparatus of the receiving-station are interrupted by the rising of the first anchor K' . Subsequently anchor F' goes upward, G' remains upon G , H' upon H , and F' interrupts contact $q\ q'$ and closes $p\ p'$. The plates b being 35 at the double distance from the plates a upon the cone C in the delivering apparatus, as b from c , a small space of time is given for the falling back of the anchor F' to the contact $p\ p'$. (See Figs. 38 and 38^a.)

45 During the turning of the first cone the type-plates d pass under the bridge B^2 , with the keys K , and the contact-plates $b\ b'\ b''$ pass under the sliding springs 1 8, the operator may stay after having pressed down the key K until the 50 second type-plates approach to the bridge B^2 , and then he may expedite the second type of his telegram. This space of time may be so short that the operator can just recite the types of his telegram and press down the corresponding keys. The continuation may be of the 55 same speed as in the Morse apparatus; but in the same time, in the space between the first and the second type of one telegram, two, three, or more types of other telegrams may pass 60 across the receiving apparatus corresponding to the number of cones. In consequence in the same time two, three, or more telegrams may be dispatched. The cone C' having turned so far that the springs 3 and 4 are sliding upon 65 plate b , springs 5 and 6 upon the plate b' , and springs 6 and 8 upon plate b'' , the second normal current will pass to the receiving-station

and will take its way, as described in the following, (see Figs. 38 and 38^a): Positive pole of battery D' , contact $g^3 h^3$, spring 3, plate b , 70 springs 4 5, plate b' , spring 6, plate b'' , spring 8. From there the current passes to that binding-screw n which is connected to the key K , pressed down respectively to the spring l , spring l will at the same time come in contact 75 with spring l' by the noses e of different lengths in different periods by the nose m . The normal current 2 is also opened and closed corresponding to the types passing under the pressed-down key. From the spring l' the current passes to the binding-post n' ; from there to the line-strap and to the line, relay apparatus of the receiving-station, earth-plate E' of the latter, back to the earth-plate E of the delivering-station, contact $h^2 g^2 g^4 h^4$, and negative pole of the battery D' . This second current, the signaling of the battery D' , induces a like one of the relay apparatus in the battery N by opening and closing the contact $a^2 a'$ and $e^2 e'$ —that is to say, this second current of the 80 battery N will be closed and opened as often and as long as the current from battery D' . The current 2 of the battery N delivers the signals in the receiving apparatus and takes its way as follows: Positive pole N , point I, 85 contact $e^2 e'$, point II, contact $x\ x'$ in $E\ III\ r\ r'$, in the same place to M in $E\ I$ (without effect to M') over $w\ q'\ p\ p'$ to the magnet L in the writing apparatus. The constant rod-magnet of the latter is placed in such a manner as to be attracted by L when normal current 2 exists, but pushed off when the current is changed. The reason for that will be evident from the following: Current 2 is a normal current. Attraction and type-writing is effected on a paper strip by a writing-pencil. From L the current 2 passes to contact $v\ v'$, point III, contact $i^2 i^3$, point III, negative pole N . After 95 finishing of this second current from N all receiving apparatuses remain unaltered, the current-circuits of the batteries O' , O^3 , and P' remain also closed, and anchor Z' and H' in E' and anchor H' in $E\ III$ sit upon the appertaining magnets. In the delivering apparatus plates b finish the passage under the springs 1 105 to 8, nose e' upon the appertaining type-plate frees the hook h^6 from h^3 of the key K pressed down, and key K rises. Now, spring i upon the upper side of C' passes under the arm g' of the plate g , the latter descends, opens the 110 contacts $g^2 h^2$, $g^3 h^3$, and $g^4 h^4$, and closes the contacts $g^5 h^5$, $g^6 h^6$, $g^7 h^7$, $g^8 h^8$. (See Figs. 8, 9, 10, 39, and 39^a.) At the same time the springs 1 and 2 slide upon the plate c and the springs 5, 6, and 7 slide upon the plate c' .

115 The current 3 of the battery D' takes its way as follows: Positive pole D' , contact $h^5 g^5$, $g^6 h^6$ to the earth-plate E of the delivering-station; from there to the earth-plate E' of the receiving station, and from there over binding-screw n' to the spring 7, over plate c' to the 120 springs 5 2, plate c , spring 1, contact $h^7 g^7 g^6 h^6$, and negative pole D' . In consequence of its current 3 is a changed current, and changes the 125

relay apparatus of the receiving station—that is to say, contact $a^2 a^3$ remains closed, $e^2 e^3$ remains opened, $i^2 i^3$ is opened, and $o^2 o^3$ and $u^2 u^3$ are closed. The current 3 of the battery N 5 takes also its way, positive pole N, point I, contact $a^3 a^2 o^3 o^2$, point III to s' in E I, over v' to the magnet L of the writing apparatus, then over contact $p' p$, through $q' w$ to the magnet m, from there to the contact $r' r$ in E III, 10 contact $x' x$, point II, contact $u^2 u^3$, point III, and negative pole N. This current takes also an irregular way. By this, magnet L' is pushed off and no signal is given. In the other case to every type a point would be 15 added. Magnet M' is attracted by this current by the magnet M, and also contact $v^2 v^3$ is opened. By this interruption of the current of battery, P' is affected, and in consequence G is demagnetized. Anchor G' rises immediately and opens $o' o'$. By this the current of the battery O' is broken, H in E III loses its magnetism, anchor H' rises, and loses the contacts $x' x$ and $z' z$.

X is fixed upon x' , and Z upon Z' in E I by 20 the effect of the battery O'. By the going backward of G' to above the contacts $r' r'$ and $s' s'$ in the same place are closed. In consequence the current from the second cone now following takes its way through the relay apparatus in the same manner as current 1 from first cone, C, and the current of the battery N caused by that passes from the positive pole of battery N to point 1, contact $e^2 e^3$, point II, contact $x' x' r' r'$ in E I (G' re-establishing the former 25 conditions by raising the contacts $r' r'$ and $s' s'$) to M in E II, from there to contact $w' u'$, magnet F, and back to E I over contact $s' s$, point III, contact $i^3 i^2$, point III, and negative pole N. The same play is taken by the three currents in 30 E II as in E I. Finally, likewise disjunction of o and o' in E II is effected. Consequently the current of the battery O' is opened and $x' x'$ in E I are closed, while in E II contact $x' x'$ continues, as before, in E I, and current 1 35 from cone E III makes the current 1 of the battery N take its way as follows: Positive pole N, point I, contact $e^3 e^2$, point II, contacts $x' x' r' r'$ in E II, magnet M in E III, contact $w' u'$, and magnet F of the same place backward to E II, over $s' s'$ to point III, contact $i^3 i^2$, point III, and negative pole N. Now, 40 current 1 from C makes the same play as before, and so forth.

The current interrupter mentioned before, 45 and represented in Figs. 37 to 39^a in full action (consisting of magnet M, steel magnet M', and contact $v^5 v^4$) is thus constructed in practice: That M', beside contact $v^2 v^3$, bears at its top also a contact, being insulated from $v^2 v^3$, but 50 working in the same manner all openings. In this second contact, named $v^5 v^4$, v^5 being the upper plate, equal to v^3 , but v^4 the lower point, v^2 , in every receiving apparatus that wire is entering, which passes from r' of 55 one apparatus to magnet M of the following apparatus. For example, in E I the wire passes not directly from r' to M in E II, but

first over $v^5 v^4$ from magnet M in E I, then to M in E II. In E II the wire passes as follows: $r' v^5 v^4$ of M in E II to M in E III. In 70 E III from r' to $v^5 v^4$ of magnet M in E III to M in E I. Contact $v^5 v^4$ would not be altered by all normal currents. It would remain closed, as $v^3 v^2$; but it would be opened by an altered current, and after the plates e have passed below the sliding spring it would be closed. 75

Every cone has its own plates, $a b c$, belonging to it, (as much alphabets, as much plate systems,) and its own sliding springs 1 to 8, and its current-interrupters g . The single-plate 80 systems are arranged every one in a third part of a circle, so that at the same time only the plate system of the signaling-cone is in full action and the sliding springs of the other cones are sliding upon wood. 85

The one arm of 7 is sliding upon a' and c' one after another, the other arm sliding over an insulated metal plate, over which three sliding springs are sliding one after another, every one being connected with a wire, 90 the first passing to binding-screw n' in the first cone, the second and the third wires passing to n' in second and third cones, respectively. Spring 8 is sliding with one arm upon b^2 . The other is in contact with an insulated plate, 95 over which, or over the prolongations of which, are passing three sliding springs, one after another, being connected to n in the several cones.

In lieu of the single batteries O', O², and O³ 100 and P', P², P³, two strong batteries, O and P, for all receiving apparatus may be applied with current division and convenient pole-contacts.

The arrangement represented in Figs. 19 to 105 24 may be modified in the following manner: Upon a common wooden frame, A, is fixed electro-magnet E², (see Fig. 41,) at the upper end, M², and rectangular to them electro-magnet x. Upon the anchor k' of E² is fixed the rod a by the onset a'. The upper onset, a', 110 grasps over the anchor k² of M². Upon the onset a' an insulated plate, b, is adapted, the pin b' of it being guided in the metallic guidance F³. The metal plate supported by the insulated plate b is the known contact e'. Below the anchor k' is adapted an insulated tag, pushing upon a metallic spring, the two forming the known contact o t. Below the anchor k² are adapted (see left hand in the drawings) 115 the contacts r s with the tag n, behind that contact l l', (see Fig. 42,) and to the right contact k k', all fitted with the known tags, springs, and arresting angles. Upon k² are fitted two insulating-plates bearing the metal plates g' g². The pencils of the insulating-plates are running in the metal cones h' and h², adapted to the wooden onsets below the frame A. Below k² is fitted an insulated metallic ring, i, leaning upon the metallic ring c, 120 its part insulated and lying upon anchor K³ of magnet x. K³ is represented in Fig. 40 in section. The holes in i and c avoid touching the rod a. If the anchor K' will be attracted by the first current of E², k² will be pushed 125 130

down, and remaining upon M^2 with the contact $k' k'$ because battery II is closed. In the same time k' , going down, loses the upper contact, f^3 e' , and closes the under contact, $o' t$. If current 5 No. 1 ceases, K' , with its two tearing springs and rod a , slides upward in its guidance, contact is closed again, and $o' t$ opened. The onset a^2 removes from K^2 . In going down anchor k^2 takes with anchor K^3 . Next this is effected 10 by the leaning of i upon e . For equal reparation of the pressure in K^2 a doubled curved plate, Q , (see Figs. 41 and 43,) is inserted, a transverse onset, Q_1 , of $K' K^3$ bears the known contacts $p' q$ and $d' f$. K^3 , sliding in guides c' 15 c^2 , is drawn off by springs in the same manner as K^2 if the functions are all finished—to wit, if the currents of the corresponding batteries are open.

In Fig. 44 on the left the arrangement of the 20 contacts $k' k'$ and $d' f$, and on the right hand the arrangement of the contacts $p' q$ are given. Fig. 42 shows the contacts $r' s$ and $l' l'$. The arresting-angles, the guidance $c' c^2$ in K^3 , and the blocks supporting the springs are represented fixed upon the wooden bobbins of the 25 wire-spoils of M^2 and x . For this purpose the upper flanges may be made somewhat heavier. The function of the apparatus is the same as before described.

30 The current-interrupter magnet M is fitted with a double lever, M' , as an anchor turning in points, and bearing on its attracting end the contacts $v^2 v^3$ on top and $v^6 v^7$ on the bottom. To the counter-weight end is fitted contact v^4 35 v^5 . In normal position v^4 is leaning against v^3 , and v^4 against v^5 . If attraction takes place, $v^2 v^3$ and $v^4 v^5$ are opened and contact $v^6 v^7$ is closed. To $v^2 v^3$ the wires enter as follows: To v^2 the 40 wire from t and to v^3 that from the winding of G . To v^4 the wire from r' enters, and passes to v^5 and to the magnet M of the following apparatus, to wit: From r' of E A I to v^4 of the magnet M in E A I; from v^5 in the same to M in E A II; from r' of E A II to v^4 of M in 45 E A II, and from v^5 of the same to M in E A III; from r' of E A III to o' of the magnet

M in E A III, and from v^5 of the same to M in E A I. The purpose of the contact $v^6 v^7$ is to make dependent the duration of the reversed current (No. 3) from the duration of 50 sliding of the plates in the delivering apparatus. In the wire conduction, as represented and described, till now the contact $v' v'$ would be lost by the rising of G' , and thus the reverse current would be broken without dependency 55 of the duration of the sliding of the current springs upon the plates; but this may cause vibrations of M' , or false currents. This is prevented by the following wire: From s' of every apparatus I II III to $v', (v'$ is a metal 60 button fixed to a spring,) to which pushes v^6 , when going down. v^6 is a tag preserving the spring from going too high. During the activity of the reversed current attracting M' to M there may be observed that v^6 pushes immediately against v' before contact $v' v'$ is lost. In such a manner the reversed current remains continual until the plates have passed, although $v' v'$ is opened.

What I claim as my invention is—

1. In an electric telegraph, the combination of a number of rotating cones provided with the dots and dashes of the Morse system, with keys, and a pawl arrangement adapted to engage the keys, and with nose e' on the cones 75 for releasing the keys, substantially as specified.

2. In an electric telegraph, the combination of a series of rotating cones with the plates g , attached to levers g' , and provided with the 80 contact-points $g^2 g^3$, with frames f , attached to plates B' , and with springs $h^2 h^3$ and springs i , attached to the cones, substantially as specified.

In testimony whereof I hereunto sign my 85 name, in the presence of two subscribing witnesses, this 30th day of December, 1886.

DAVID KUNHARDT.
